ADJUSTABLE LOAD SUPPORT

Ingram V. Stovern and Wendell L. Vallee, Sheboygan, Wis., assignors to Blackhawk Mfg. Co., West Allis, Wis., a corporation of Wisconsin

Application May 21, 1956, Serial No. 586,225

2 Claims. (Cl. 254—134)

This invention relates in general to improvements in devices for supporting diverse loads in a stable manner, and relates more specifically to improvements in the construction and operation of adjustable load supporting saddle assemblages for lifting jacks or the like.

The primary object of our invention is to provide an improved load supporting unit which can be readily adjusted to vary the point or points of application of the lifting force applied to the supported loads by a jack or the like.

It has heretofore been well known practice to utilize jacks of various types provided with saddles applicable to the bumpers of diverse vehicles in order to raise and lower the latter. In some of these prior jack assemblages the lifting force was applied to one or more load engaging saddles through a transverse supporting bar or beam along which the saddle or saddles could be slidably adjusted to vary the point or points of application of the force; and in case a pair of saddles were provided, the distance between these saddles could also be varied by moving the saddles toward or away from each other. However, in these prior lifting units, the saddles were either slideable along their supporting bar or were welded to the bar which in turn was telescopically slideable within a tubular member, and in either case, the range of adjustment was relatively limited while the coacting saddle and beam surfaces would also oxidize and cling together thus making it difficult to make any adjustments.

It is therefore an important object of the present invention to provide an improved adjustable lifting saddle assemblage in which one or more saddles carried by a supporting beam are readily disposable either at an end or near the center of the latter without necessity of sliding the saddles along the bar.

Another important object of this invention is to provide an improved lifting jack unit especially applicable to the bumpers of vehicles, and wherein the position of the points of engagement between the lift and the bumper can be quickly changed to produce safe elevation and holding of the vehicle in raised condition.

A further important object of the invention is to provide a simple but highly effective lifting and supporting device for vehicles or the like, wherein one or more load engaging saddles are swingably adjustable to various positions along a transverse carrying beam to which the lifting force is applied from beneath.

Still another important object of the invention is to provide a load supporting and lifting accessory which is readily applicable to various types of jacks to provide a lift which is extremely flexible in its adaptations.

An additional important object of our invention is to provide a durable adjustable load support comprising a supporting bar or beam and one or more work engaging saddles adjustable therealong to convert the assemblage from a two point lifting device to a single point lifting device, and wherein the several parts are prevented from becoming dismantled and lost.

2

These and other more specific objects and advantages of the invention will be apparent from the following description.

A clear conception of the several features constituting the present improvement and of the construction and functioning of a jack assemblage embodying the invention, may be had by referring to the drawing accompanying and forming a part of this specification in which like reference characters designate the same or similar parts in the various views.

Fig. 1 is a front elevation of a typical mechanical vehicle lifting jack having an improved commercial supporting beam and saddle assemblage applied thereto, and showing the saddles disposed close together;

Fig. 2 is a part sectional side view of the same lifting unit, the section having been taken along the line 2—2 of Fig. 1;

Fig. 3 is a fragmentary front elevation of the same unit similar to that of Fig. 1, but showing the load engaging saddles spread apart to the maximum extent; and

Fig. 4 is a fragmentary top and front perspective view of the supporting beam and one of the work engaging saddles alone.

While the invention has been shown and described herein as having been applied to a mechanical vehicle lifting and lowering jack especially adapted for application to the bumpers of diverse vehicles such as trucks and automobiles, it is not the intent to restrict the use of the improvements to such applications; and it is also contemplated that specific descriptive terms employed herein be given the broadest possible interpretation consistent with the disclosure.

Referring to the drawing, the improved mechanical jack assemblage shown therein, comprises in general, a chassis having a base 6 and an upstanding guide 7 and being provided with rear supporting legs 8 secured to the base 6 and guide 7; a rotary screw shaft 9 journaled at its opposite ends in the guide 7 and having a manipulating handle 10 secured to its upper extremity while its screw threads coat with longitudinally movable nut 11; an elevator 12 slideable along the chassis guide 7 by the nut 11 and having a pair of forward projections 13 rigidly secured to the medial portion of a transverse bar or beam 14 the opposite ends of which are provided with stop pins 15; and a pair of load supporting saddles 16 each having several independent work engaging upper surfaces 17, 18 and a lower loop portion 19 embracing the beam 14 between the pins 15.

The chassis base 6 and guide 7 may be formed of structural steel while the legs 8 may be constructed of metal tubing, and the guide 7 is inclined rearwardly so as to position the load within the base, while the legs 8 are bent and provided with jack transporting wheels 21 located near the bends as shown in Fig. 2, the wheel and axle assemblage being carried either directly by the legs 8 or by a special wheel bracket welded or otherwise secured to the legs. The screw shaft 9 has its opposite ends mounted in bearings 22 secured within the chassis guide 7 so that this shaft cannot move longitudinally but is rotatable by the handle 10, and this handle may be swung forwardly as illustrated in dot-and-dash lines in Fig. 2, when not in use. The nut 11 which coats with the screw threads of the shaft 9 engages an angle iron 23 which is slideable within and along a rear slot 24 in the guide 7 and is rigidly attached to the rear of the elevator 12, and this elevator slideably embraces the chassis guide 7 and is provided with plastic or nylon bearing buttons 25 coating with the outer guide surface.

The present improved load supporting assemblage comprises the approximately horizontal transverse bar or beam 14 which is formed of solid bar stock, and the two saddles 16 which are of identical formation and

are constructed of sheet metal or steel plate material and angle iron stock welded together. The upper wall portions of each saddle 16 are flared outwardly as depicted in Figs. 2 and 4, and the transverse angle iron upon which the load engaging surfaces 17, 18 are formed are welded to these upper wall portions so as to form the saddle socket. The lower loop portion 19 of each saddle 16 is provided with a pair of off-set upper and lower transverse elements 27, 28 respectively which are co-operable with the top and bottom surfaces of the beam 14, and the saddles 16 may be interchangeably rocked relative to the beam 14 from the position illustrated in Fig. 1 to that shown in Figs. 3 and 4, or vice versa. The end pins 15 of the supporting beam 14 merely act as stops for preventing the saddles 16 from being removed from the cross-bar.

When the lifting unit has been properly constructed and assembled as hereinabove described, it may be transported from place to place by tilting the entire assemblage rearwardly to cause it to rest upon the wheels 21, or it may be set up for normal use as in Figs. 1 and 2 with the base 6 and lower leg portions resting upon the ground. If it is desired to have the saddles 16 coact with a load such as a vehicle bumper with the contact points spaced apart as far as possible, then the saddles should be positioned against the stop pins 15 with the saddle surfaces 18 directed upwardly as in Fig. 3. If it becomes desirable to have a single saddle contact point engageable with the bumper, then the saddles 16 may be rocked toward each other about the beam 14 to upwardly direct the other saddle surfaces 17 as in Fig. 1, whereupon the two saddles 16 may also be slid into actual abutting engagement with each other in central alignment with the jack.

The two saddles 16 may also be moved along the supporting beam 14 to any intermediate position to present either set of surfaces 17, 18 toward the load, and when the jack has been properly positioned relative to the work, the handle 10 may be manipulated to rotate the screw shaft 9 and to raise the nut 11 and the elevator 12 until the load is lifted the desired amount by the saddles 16. While both saddles 16 would ordinarily be utilized in order to concentrate the load in or near the central vertical plane of the chassis guide 7, it is also possible to lift loads with the aid of only one of the saddles 16, and the suspended loads may be readily lowered by reversely revolving the handle 10 and the screw shaft 9. When the jack assemblage is not in use, the saddles 16 may be swung inwardly and the handle 10 may be swung forward as shown in dot-and-dash lines in Fig. 2, so as to occupy minimum storage space.

From the foregoing detailed description it will be apparent that the present invention in fact provides a simple, compact and durable work engaging saddle assemblage which is highly flexible in its adaptations to meet varying conditions of use. The swingable cooperation of the saddles 16 with the supporting beam 14 combined with the slidability of the loop portions 19 along this beam obviously provides means for quickly and effectively locating the saddles in any desired position for proper coaction with the loads, and the bar and saddle are maintained in assembled condition by the pins

15. Whenever a load is applied either to the surfaces 17 or interchangeably to the surfaces 18 of the saddles 16, the transverse elements 27, 28 of the loops 19 coact with the top and bottom respectively of the supporting beam 14 to effectively transmit the lifting force to the load while holding the saddles firmly in position. The entire assemblage may be manufactured at moderate cost from available steel plate, angle iron and metal tubing, and the improved saddles have proven highly 10 satisfactory and successful in actual use.

It should be understood that it is not desired to limit this invention to the exact details of construction and operation of the adjustable load support herein shown and described, since obvious modifications within the 15 scope of the appended claims may occur to persons skilled in the art.

We claim:

1. In a load carrier for a vehicle jack, an elongated rigid horizontal beam having its mid-portion formed for 20 attachment to the lifting member of the jack, and a pair of unitary sheet-metal supports slidably and swingably adjustable relatively to each other on said beam, each of said supports having spaced side walls flared outwardly and united at their upper ends to form a 25 saddle by an integral transverse element provided with adjoining load engaging surfaces disposed at an angle relative to each other while the lower side wall ends are united by integral upper and lower transverse off-set beam engaging elements to provide a loop snugly but slidably 30 embracing the beam, said supports being swingable toward or away from each other relative to said beam about said lower elements to alternately present said adjoining saddle surfaces to the load at various positions along the beam, and the supports also being bodily 35 slidable along said beam when swung either toward or away from each other to likewise present said saddle surfaces at various positions along the beam.

2. In a load carrier for a vehicle jack, an elongated rigid horizontal beam having its mid-portion formed for 40 attachment to the lifting member of the jack, and a pair of load supports slidably and swingably adjustable relatively to each other on said beam, each of said supports having spaced side walls united at their upper ends to form a saddle by an integral transverse element provided 45 with load engaging surfaces disposed at an angle relative to each other while the lower side wall ends are united by integral upper and lower transverse off-set beam engaging elements to provide a loop snugly but slidably embracing the beam, said supports being swingable toward or away from each other relative to said beam about said lower elements to alternately present said saddle surfaces to the load at various positions along the beam, and the supports also being bodily slidable along said beam when swung either toward or away 50 from each other to likewise present said saddle surfaces at various positions along the beam.
